US0D1036420S

(12) **United States Design Patent** (10) **Patent No.:** **US D1,036,420 S**
(45) **Date of Patent:** **** Jul. 23, 2024**

(54) **ELECTRONIC DEVICE**

- (71) Applicant: **Amazon Technologies, Inc.**, Seattle, WA (US)
- (72) Inventors: **Sun Joo Han**, San Francisco, CA (US); **Giles David Matthew McWilliam**, San Francisco, CA (US)
- (73) Assignee: **Amazon Technologies, Inc.**, Seattle, WA (US)

(**) Term: **15 Years**

(21) Appl. No.: **29/911,249**

(22) Filed: **Aug. 30, 2023**

Related U.S. Application Data

(62) Division of application No. 29/800,301, filed on Jul. 20, 2021, now Pat. No. Des. 1,008,221, which is a division of application No. 29/650,576, filed on Jun. 7, 2018, now Pat. No. Des. 931,834.

CLAIM

The ornamental design for an electronic device, as shown and described.

DESCRIPTION

FIG. 1 is a top, front, right-side perspective view of an electronic device;

FIG. 2 is a bottom perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dashed broken lines depict portions of the electronic device that form no part of the claimed design.

1 Claim, 8 Drawing Sheets
